Int. Cl. D21—04

FIG. 2.

FIG. 3.

FIGURE 1 is a top plan view of a billiard table or similar article showing my new design;

FIGURE 2 is a side elevational view;

FIGURE 3 is an end elevational view;

FIGURE 4 is a side elevational view wherein the sides and legs are provided with ornamental surface treatment; and

FIGURE 5 is an end elevational view of the embodiment shown in FIGURE 4.

The top of the embodiment shown in FIGURES 4 and 5 is the same as that shown in FIGURE 1. The sides opposite those shown in FIGURES 2 and 4, and the ends opposite those shown in FIGURES 3 and 5, are substantially similar to those shown.

I claim:

The ornamental design for a billiard table or similar article, as shown and described.
